Primary Examiner — Rhea Shields(74) *Attorney, Agent, or Firm* — GTC Law Group PC & Affiliates(57) **CLAIM**

The ornamental design for a plug, as shown and described.

DESCRIPTION

FIG. 1 is a front perspective view of an embodiment of our new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof; and,

FIG. 7 is a bottom plan view thereof.

In the Drawings, the broken lines depict environment only and form no part of the claimed design.
